Elijah P. Penniman, Rochester, N.Y.
Letters Patent No 177, dated 18th April 1848

The Schedule referred to in these letters Patent and making part of the same.

To all whom it may concern.

Be it known that I Elijah P.
Penniman of the City of Rochester County of Monroe and State of New York have invented a new ornamental design for Gloves and I do hereby declare that the nature of my invention is fully represented by the accompanying drawing, and model. What I claim

2

Dec. 1747

as my invention and desire to secure by letters patent is the combined ornamental arrangement as described by the accompanying drawing and model to be used in fixtures as described on the drawing by the letters B and N.
